US00D757762S

(12) United States Design Patent
Guesnon, Jr.

(10) Patent No.: US D757,762 S
(b4) Date of Patent: * May 31, 2016

(54) DISPLAY SCREEN OR PORTION THEREOF
WITH GRAPHICAL USER INTERFACE

(71) Applicant: Thales Avionics, Inc., Irvine, CA (US)

(72) Inventor: Andrew A. Guesnon, Jr., Anaheim Hills, CA (US)

(73) Assignee: Thales Avionics, Inc., Irvine, CA (US)

() Term: 14 Years

(21) Appl. No.: 29/451,671

(22) Filed: Apr. 5, 2013

(51) LOC (10) Cl. 14-04

(52) U.S. Cl.

USPC D14/486

(58) Field of Classification Search

USPC D14/485-495; 715/700, 702, 716, 719, 715/726, 733, 763, 765, 781, 783, 810, 835, 715/864

CPC ... G06F 3/0482; G06F 3/0484; G06F 3/0485; G06F 3/0486

(57) CLAIM

The ornamental design for a display screen or portion thereof with graphical user interface, as shown and described.

DESCRIPTION

The FIGURE is a front view of a display screen or portion thereof with graphical user interface showing the new design. The broken lines shown in the FIGURE represent portions of the display screen or portion thereof with graphical user interface that form no part of the claimed design.

1 Claim, 1 Drawing Sheet
